STRINGED INSTRUMENT AUXILIARY BASS-BAR AND SOUND PLATE

Rex Arlington, Huntington, Ind.

Application June 3, 1954, Serial No. 434,185

6 Claims. (Cl. 84—276)

This invention relates to stringed instruments, particularly of the violin family, and in particular an elongated strip of material having a relieved portion in the intermediate part thereof positioned against the under surface of the top of the box or body of a violin, or the like, on the E string side of the bass-bar and directly below the D and G strings and a sound plate also secured to the under surface of the top of the instrument, positioned directly under the bridge, centered slightly behind the bridge and particularly under the E string foot of the bridge.

The purpose of this invention is to provide an improved violin having an extraordinary singing tone with improved carrying power and wherein higher positions on all strings are more easily obtained and which respond more readily with various types of double stops; and which also provides single and double harmonics in both natural and artificial tone characteristics.

Various attempts have been made to use bass-bars and other reinforcing or sound modifying elements in tone chambers of violins, however, in order to obtain desired results it is essential that these elements be positioned on the E string side of conventional bass-bar and under the D and G strings of the instruments. With this thought in mind, this invention contemplates an elongated bass-bar having tapering ends and having a recess in the intermediate portion separating the intermediate portion from the top of the instrument and wherein the bass-bar extends substantially throughout the length of the box and is positioned at one side of the conventional bass bar. The invention also contemplates a sound plate positioned under the bridge and centered behind the E string foot of the bridge wherein the sound plate is set at a right angle to the bridge or positioned parallel with the longitudinal axis of the violin body with the center resting on top of the sound post so that the sound plate diffuses and intensifies vibrations from the A and E strings.

The object of this invention is, therefore, to change the design and the position of bass-bars of stringed instruments whereby extraordinary singing tones and improved carrying power are obtainable.

Another object of the invention is to provide means for forming an auxiliary bass-bar for a stringed instrument whereby tension is provided in the bass-bar which strengthens and intensifies the tone of all strings of the instrument and particularly the tones of the lower or D and G strings.

Another object of the invention is to provide a sound plate for stringed instruments which diffuses and intensifies the vibrations particularly of the A and E strings of the instrument.

A further object of the invention is to provide improvements in the sound chamber of a stringed instrument particularly of the violin family in which an auxiliary bass-bar and a sound plate improve the tone values of all strings and more particularly the lower or D and G strings, the tone values being strengthened and intensified, and in

2

which the improved instrument is of a comparatively simple and economical construction.

With these and other objects and advantages in view the invention embodies an elongated strip of material, such as spruce, having ends of gradually reducing thickness with a recess in the intermediate portion providing an auxiliary bass-bar, positioned against the conventional bass-bar of the instrument and against the under side of the top thereof and a sound plate, also of a suitable material, such as spruce, also positioned against the under surface of the top of the instrument and below the bridge whereby tones particularly of the lower strings, such as the D and G strings, are strengthened and intensified.

Other features and advantages of the invention will appear from the following description taken in connection with the drawing, wherein:

Figure 1 is a view looking toward the under surface of the top of a violin body showing the auxiliary bass-bar and sound plate in position thereon.

Figure 2 is a longitudinal section through the top taken on line 2—2 of Fig. 1 showing the conventional bass-bar with the auxiliary bass-bar on the far side thereof.

Figure 3 is a section similar to that shown in Fig. 2, taken on line 3—3 of Fig. 1, showing the sound plate and auxiliary bass-bar, the sound plate being positioned to correspond with a relieved portion or recess in the surface of the auxiliary bass-bar in contact with the under surface of the top.

Figure 4 is a cross section through a violin body taken on line 4—4 of Fig. 1, showing both upper and lower portions and also side walls of the body, and illustrating the positions of the auxiliary bass-bar and sound plate on the upper portion or top thereof.

Referring now to the drawing wherein like reference characters denote corresponding parts, the improved auxiliary bass-bar of this invention, which is referred to by the numeral 10, is provided with tapering ends 11 and 12 and this bar is positioned at one side of the conventional bass-bar 13 of the violin.

The invention also includes a sound plate 14 which, as shown in Fig. 1, is positioned directly under the bridge and centered slightly behind the bridge and under the E string foot thereof.

As shown in Fig. 1, the sound plate is set at a right angle to the bridge whereby it extends parallel with the longitudinal axis of the violin body with the center thereof resting on top of the sound post whereby the sound plate diffuses and intensifies vibrations from the A and E strings.

The auxiliary bass-bar 10, which is patterned particularly as illustrated in Fig. 3, is provided with a relieved portion between the surface of the bass-bar and inner surface of the top 15 of the violin body and with the auxiliary bass-bar secured, such as by a suitable adhesive, to the instrument top tension will be provided in the bar that intensifies vibration particularly of the lower or D and G strings.

Although it is not intended or desired that the improved bass-bar be limited in size, as an illustration, it is preferred to use a strip of spruce 11½ inches in length and substantially ¾ of an inch wide with the intermediate portion tapered from ¼ of an inch thick at the ends to substantially ⅛ of an inch in depth at the center and to provide tension in the bass-bar it is necessary to provide a recess in the surface positioned toward the under surface of the top of the instrument with the recess ⅛ of an inch in depth and extended substantially ¾ of the length of the auxiliary bass-bar. This bass-bar is positioned against the conventional bass-bar and on the E string side thereof with the improved bass-bar extending particularly below the lower or D and G strings.

The sound plate, which may also be made of spruce, is substantially one inch wide by two inches long and this

plate is substantially $\frac{1}{16}$ of an inch in thickness. This plate is preferably glued to the top directly under the bridge and centered about $\frac{3}{8}$ of an inch behind the bridge under the E string foot thereof. The sound plate is set at a right angle to the bridge or parallel to the longitudinal axis of the violin body whereby the center rests on top of the sound post whereby the sound plate diffuses and intensifies vibrations from the A and E strings.

With the auxiliary bass-bar and sound plate positioned in this manner the improved sound chamber of a violin strengthens and intensifies the tone of all strings and more particularly the lower or D and G strings, the sound plate diffusing and intensifying the vibrations of the A and E strings.

The remaining portions of the violin or other stringed instrument are conventional, the neck, bridge and frets being as usual.

Only the very best instruments of the string family are satisfactory for playing great classical music requiring the use of the higher positions, double stops and harmonics and with the bass-bar and sound plate of this invention installed in a moderate type of instrument the instrument is perfectly responsive to all technical difficulties making it possible to use higher positions on all strings with all kinds of double stops, single and double harmonics and with both natural and artificial tones. With such an instrument a player appreciates that an extraordinary singing tone with extensive carrying power is provided. These elements also permit the use of a higher and thinner bridge and make it possible to play double stops and both single and double harmonics and the high tones are readily distinguished on all strings, particularly on the E string. The use of this auxiliary bass bar also makes the central tone more readily distinguished, making for better intonation and gives the tone of the violin an entirely different timbre, not merely enhancing what it already has, but giving it a different tone.

It will be understood that modifications, within the scope of the appended claims, may be made in the design and arrangement of the parts without departing from the spirit of the invention.

What is claimed is:

1. A stringed instrument body having a top, an auxiliary bass-bar positioned against the under surface of the top of the instrument body and against one side of the conventional bass-bar, the length of the auxiliary bass-bar being greater than that of the conventional bass-bar whereby the ends of the auxiliary bar extend beyond the ends of the conventional bar, and a sound plate also adapted to be positioned against the under surface of the top of the instrument body.

2. A stringed instrument body having a top with a conventional bass-bar on the under surface, an auxiliary

bass-bar also mounted on the under surface of the top, located on the E string side of and against the surface of the conventional bass-bar and a sound plate on the under surface of the top positioned under the bridge and slightly behind the E string foot thereof.

3. A stringed instrument body having a top with a conventional bass-bar on the under surface, an auxiliary bass-bar also positioned on the under surface of the top, on the E string side of the conventional bass-bar and against the surface of said conventional bass-bar, and a sound plate on the under surface of the top positioned under the bridge and slightly behind the E string foot thereof, said auxiliary bass-bar having a recess in the surface position against the under surface of the top and 15 in the intermediate part thereof.

4. A stringed instrument body having a top with a conventional bass-bar on the under surface, an auxiliary bass-bar also positioned on the under surface of the top, on the E string side of the conventional bass-bar and 20 against the side surface of said conventional bass-bar, and a sound plate on the under surface of the top positioned under the bridge and slightly behind the E string foot thereof, said auxiliary bass-bar having means for providing tension therein.

5. In a stringed instrument, the combination which comprises an instrument body top having a conventional bass-bar on the under surface thereof, an auxiliary bass-bar, the length of which is greater than that of the conventional bass-bar, also mounted on the under surface 30 of the top and positioned on the E string side of the conventional bass-bar and against the surface of said bass-bar, and a sound plate mounted on the under surface of the instrument body top and positioned directly under the bridge of the instrument.

6. In a sound chamber for stringed instruments, the combination which comprises an instrument body top having a bridge and having a conventional bass-bar on the under surface thereof, an auxiliary bass-bar having tapering ends and having a recess in the intermediate 40 portion and in the surface thereof positioned against the under surface of the instrument body top and positioned on the E string side of the conventional bass-bar and against the surface of said conventional bass-bar, and a sound plate mounted on the under surface of said top and positioned below the bridge and particularly under the E string foot thereof and said sound plate being parallel to the longitudinal axis of the instrument body.
